UNITED STATES PATENT OFFICE.

DANIEL CUDWORTH, OF SHELBOURNE, MASSACHUSETTS.

FINE-FUEL FURNACE.

No. 890,028.

Specification of Letters Patent.

Patented June 9, 1908.

Application filed September 27, 1907. Serial No. 394,851.

To all whom it may concern:

Be it known that I, DANIEL CUDWORTH, of Shelburne, in the county of Franklin and State of Massachusetts, have invented certain new and useful Improvements in Fine-Fuel Furnaces, of which the following is a specification.

My device relates to that class of improvements which secure the combustion of coal and other inflammable substances by feeding the same to the combustion chamber by means of pressure and the object is to regulate the supply of coal and air, or steam, so as to secure perfect combustion. I attain these objects by the means illustrated in the accompanying drawings, in which

Figure 1. shows a cross sectional view of said device. Fig. 2 is a plan view of the grate and parts of the furnace. Fig. 3 is a sectional view of the valve regulating the flow of coal.

a represents a pipe which is attached to a blower or which may be connected with a steam pipe; *b* represents a pipe communicating with a front part of furnace and with the pipe *a*; *c* represents the outlet of the pipe *a* through which the contents enter the lower part of the furnace *s*, and the end of pipe *a* is so arranged as to discharge a stream 30 of air or steam toward the front of furnace from which direction it is deflected upward by the guides *t* to meet the discharge from the pipe *b*, *d* is a receptacle for coal, *e* is a pipe through which the coal passes 35 from the receptacle *d* into the chamber *f* and through the pipe *g* into the chamber *h*. A hinged part at *i* permits the regulation of the mouth of the chamber *h* by means of the rod *j* which extends through the opening *k* and is connected to the part *i* at *q*. A transparent substance at *l* permits a view 40 of the chamber *h*, *m* represents a valve which is hinged at *n* and which is connected with a screw at *o*. The air or steam is injected into the pipe by means of a fan or steam pressure, and the flow through the outlet at *c* is regulated by the valve *a'* which may be of any ordinary construction. The valve *b'* may also be of any ordinary construction.

It is apparent that when the coal passes from the receptacle *d* and falls into the

chamber *h* that the fluid passing through the pipe *b* will cause the coal to pass into the fire box, in which it is designed to have fire 55 when the coal is injected, and that the air or steam coming out of the pipe *a* at *c*, if under sufficient pressure will cause the coal to be suspended until it has been consumed.

y represents a bridge wall which is elevated at *z* above the grate *t*. The part of said bridge wall *y* nearest the rear of the furnace is extended obliquely from *v*.

s represents a chamber under the grate into which the air passes through the pipe *a* 65 at *c*.

t represents hooks for attaching the plates *t* to the grate.

The proper mixing of the coal and air or steam is of the utmost importance in this 70 class of furnace attachments and this object has heretofore been imperfectly attained. The valves *a'* and *b'* permit of the regulation of the quantity passing through the pipes *a* and *b* into the furnace at both *h* and *c*, and 75 the valve *m* regulates the flow of coal so that the quantity of each admitted is always subject to regulation independently of each other.

Having thus described my invention, what 80 I claim as new and desire to secure by Letters Patent, is

1. In a fine fuel furnace, the combination with a fire box, and an ash pit of a grate separating the fire box from the ash pit, a plurality of deflectors carried by said grate and depending into the ash pit, the lower ends of said deflectors being curved rearwardly and each of said deflectors being slightly shorter than the one in front of it, a chamber for coal, 90 means for supplying compressed air to said chamber, and a second pipe located at the rear of the ash pit and discharging toward said deflectors.

2. In a fine fuel furnace, the combination with a fire box and an ash pit, of a grate separating the fire box from the ash pit, a plurality of deflectors carried by said grate and depending into the ash pit, the lower ends of said deflectors being rearwardly curved and each of said deflectors being slightly shorter than the one in front of it, a chamber for coal located at the mouth of the fire box, means for supplying coal to said chamber through

the top thereof, means for supplying compressed air to said chamber to blow the said coal therefrom, a second pipe located at the rear of the ash pit and discharging toward said deflectors, a hinged closure for the mouth of the coal chamber, and a lever connected to said hinged closure, said lever passing through

5 the upper wall of the chamber and then

through the rear wall thereof to the exterior of the furnace.

In testimony whereof I have affixed my signature, in presence of two witnesses.

DANIEL CUDWORTH.
